UNITED STATES PATENT OFFICE.

FRANK H. DICKSON, OF OSWEGO, NEW YORK.

CHAIN WRENCH.

1,055,148

Specification of Letters Patent. Patented Mar. 4, 1913.

Application filed July 12, 1912. Serial No. 709,038.

To all whom it may concern:

Be it known that I, FRANK H. DICKSON, a citizen of the United States, residing at Oswego, in the county of Oswego and State 5 of New York, have invented certain new and useful Improvements in Chain Wrenches; and I do hereby declare the following to be a full, clear, and exact description of the invention, such as will enable others skilled 10 in the art to which it appertains to make and use the same:

My invention relates to an improvement in chain wrenches, and particularly to improvements on the construction disclosed in 15 U. S. Patent No. 1,023,198 granted to me April 16, 1912.

In the patent above referred to the jaws are secured to the handle by a single bolt, and the chain is secured to a bolt passing 20 through the jaws, and blocks in advance of the handle.

The object of this invention is to strengthen the wrench at the point where the chain is attached, and it consists in a handle, two 25 blocks each recessed to receive the end of the handle between them and each provided with two hooks, two jaws each recessed on its inner face to form seats for the blocks, two bolts both passing through the jaws, 30 blocks and handle and a chain mounted on one of said bolts and adapted to engage the hooks on the blocks.

In the accompanying drawings, Figure 1 is a view in elevation partly in section of 35 my improved wrench. Fig. 2 is a view in longitudinal section, showing the bolts in elevation. Fig. 3 is a view in transverse section through the center of the jaws, showing the bolt in elevation. Fig. 4 is a view in 40 elevation of one of the jaws. Fig. 5 is a view in perspective of one of the blocks, and Fig. 6 is a view in section taken through the bearing for the center bolt but showing the shoulders continuous and the projection 6 45 cut away on their outer sides and overlapping said shoulders.

1 represents the jaws, each of which is elliptical in shape and provided with teeth or serrations at both ends so that the wrench 50 may be used either side up, and the jaws may be reversed end for end. Each jaw is recessed or provided with shoulders on its inner face as at 2, to receive the blocks 5, and the outer edges of the latter conform to 55 the contour of the recess or shoulders at

each end of the jaw so that when seated in said recess it will be supported and sustained by engagement with the walls of said recess or with said shoulders. If desired each flange or wall 3 of the recess 2 may be cut 60 away centrally as shown to receive the angular projection 6 at the front ends of the blocks, but this is not essential, as the angular projection may be cut away so as to overlap said walls. 65

5 are the blocks, one for each jaw provided adjacent their front ends with the oppositely disposed angular projections 6, which terminate approximately flush with the edges of the jaws. The portions of the 70 jaws in rear of the angular projections 6 conform to the shape of the recesses in the jaws at one side of the center, so that when the parts are assembled, the jaws are supported by the walls of the recesses 2, and 75 not by the bolts or either of them, the latter serving primarily to hold the parts in position.

The rear or inner face of each angular projection on the block is shaped to form a 80 hook 7, with which the projecting pintles on chain 8 engage as will be hereinafter explained, and each block is also provided on its inner face with an angular recess to receive the squared end 9 of the handle 10. 85 The squared end of the handle rests between and in contact with both blocks, and within the angular recesses in the blocks, and the latter rest within the jaws, hence it will be seen that all strains imparted to the 90 jaws are transmitted directly to the handle through the blocks, and not through the bolts.

The jaws, blocks and handle are secured together by two bolts 11 and 12, both of 95 which pass through both jaws and blocks and through the handle which is enlarged as at 13 at both sides of bolt 11. One of these bolts is located approximately in the center of each jaw and the other to the rear of the center, which necessitates three bolt holes in the jaws so as to permit a reversal of the latter end for end. Both bolts are preferably threaded on both ends and are secured in place by nuts, and the bolt 12 is 100 preferably enlarged at its center so as to form shoulders 12^a which bear against the inner faces of the blocks and tend to prevent a collapsing action of the jaws when under heavy strains. The enlarged center of the 110

bolt 12 rests within the hole in the handle and the latter is bifurcated at its front end to receive the head of link 13 of the chain 8. The head of this link is preferably as wide as the slot or bifurcation in the handle, so that it has bearing against and supports the bifurcated members of the handle against the side pressures.

The chain may be composed of flat links connected by pintles 14 which project at both sides so as to engage the hooks 7, or they may be composed of ordinary looped chains as shown in dotted lines in Fig. 2.

The inner or adjacent faces of the blocks are separated sufficiently for the reception of the links of the chain but not for the pintles 14. The hooks 7 are of a size and shape to enter between the pins of two adjacent links, or between the links of an ordinary looped chain, and engage the pintle, or the end of the next link thus locking the chain against the possibility of accidental dis- placement after it has been placed around a pipe or other object and put under tension.

In the use of the wrench, the chain is passed around the pipe or other object to be turned and secured to the hooks 7. The chain therefore holds the serrated jaws against the pipe in such position that when the lever or handle is actuated the teeth or

serrations in the jaws will grip the pipe and turn the same in the well known manner.

Having fully described my invention what I claim as new and desire to secure by Letters-Patent, is:—

In a chain pipe wrench, the combination of a handle having an angular bifurcated end, two blocks each recessed to receive the angular end of the handle and each provided with two blocks, two jaws each provided with abutments on its inner face to engage the edges of the block and form supports for the same, a bolt having an enlarged center with straight shoulders at the ends of the enlargement, the said bolt passing through the jaws, blocks and bifurcated end of the handle, the shoulders on the bolt bearing against the inner faces of the blocks, a second bolt passing through the jaws, blocks and handle in rear of the shouldered bolt and a chain mounted on the enlarged portion of the shouldered bolt and adapted to engage the hooks on the blocks.

In testimony whereof, I have signed this specification in the presence of two sub- 55
scribing witnesses.

FRANK H. DICKSON.
